UNITED STATES PATENT OFFICE

2,512,047

AIR CONTROL VALVE FOR OIL BURNERS

Henry Weyenberg and Cornelius Quist, Holland,
Mich., assignors to Holland Furnace Company,
Holland, Mich., a corporation of Delaware

Application June 22, 1944, Serial No. 541,505

3 Claims. (Cl. 251—9)

1

This invention relates to oil burners of the type employed principally in connection with domestic heating plants and is concerned especially with certain features of such apparatus including an adjustable air controlling means for the supply of air for combustion in the burner.

One of the objects of the invention is to provide a new and improved air control device for an oil burner. Another object of the invention is to provide air supply apparatus for an oil burner including an adjustable air inlet of relatively simple design adapted for economical manufacture. It is also an object of the invention to provide a regulating valve for the air supply of an oil burner which shall be adjustable through a wide range for adapting the burner mechanism to operate at various speeds and with various hydrocarbon fuels.

More specifically, it is an object of the invention to provide air control means in combination with a blower of the centrifugal type in which the central inlet opening of the blower is closed by a cover having an annular wall with an elongated port extending circumferentially therein and with a circumferentially slidable valve or cover member for said port adjustable to vary the effective capacity of the port.

Other objects and advantages of the invention will appear from the following description taken in connection with the drawings in which:

Fig. 1 is a side elevation showing an oil burner of the type to which this invention is adapted and in which it is embodied.

Fig. 2 is a front elevation of the same looking into the air tube from which the fuel mixture is discharged into the furnace.

Fig. 3 is a section as indicated at line 3—3 on Fig. 1 and also at line 3—3 on Fig. 4, showing the interior construction of the air control device.

Fig. 4 is a section taken as indicated at line 4—4 on Fig. 3.

Fig. 5 is a fragmentary detail section at line 5—5 on Fig. 4.

Fig. 6 is a fragmentary vertical sectional view taken as indicated at line 6—6 on Fig. 2, to show the construction of the choke.

Fig. 7 is a detail section taken as indicated at line 7—7 on Fig. 6.

Fig. 8 is a detail sectional view taken as indicated at line 8—8 on Fig. 1 and on a larger scale.

While we have shown in the drawings and have herein described in detail a preferred form of our invention, it is to be understood that we do not intend to limit the invention to the specific

2

form or application disclosed, but aim to cover all modifications and alternative constructions falling within the scope of the invention as expressed in the claims.

5 The oil burner shown in the drawings is usually supported in any convenient manner in front of the furnace or boiler with which it is associated and it includes means for supplying liquid fuel of the hydrocarbon type, together with a quantity of air, to form a combustible mixture; and these ingredients are supplied at a proper pressure and velocity to insure projection and propagation of the flame within the furnace. In the present structure the air is furnished by a blower 15 of the centrifugal type enclosed in a housing 1 to one side of which housing there is attached a driving motor 2. Fig. 2 shows the rotor 3 of the centrifugal blower in dotted outline within the housing 1, and shows the shaft 4 extending from the rotor 3 to a pump 5 which serves to feed the liquid fuel to a discharge nozzle 6, located in the air tube 7 and seen near the outer end of the tube where a portion of the wall is broken away to disclose the interior structure. 20 25 From the pump 5 a feed pipe 8 leads through the side wall 9 of the air discharge chamber 10 which is integral with and surmounted by the blower housing 1.

The blower fan or rotor 3 is of the type which receives air at one side of its central portion and discharges it centrifugally into the housing. For controlling the air thus supplied to the rotor 3, there is mounted on the side of the housing 1, and interposed between it and the pump 30 35 40 45 50 55 5, an annular shell 11 having lugs 12, 12 by which it is bolted in position over a circular opening 13 in the wall of the housing 1. The lugs 12, 12 are integral with the flange 14 which seats upon the margin of the wall surrounding the opening 13, and the shell 11 includes an annular flange 15 which extends from the seating plane of the flange 14 and into the housing 1 adjacent one side of the rotor 3. The flange 15 is somewhat tapered so as to direct the air toward the central portion of the blast wheel or rotor 3.

The shell 11 includes an end wall 16 with a central boss 17 fitting over the pump bearing in which the shaft 4 is journaled. The annular wall 50 of the shell 11 is formed with a segmental opening 20 extending from the edge 18 to the edge 19 in said annular wall and including an arcuate area 20a of the same angular extent in the end wall 16 of the shell. This opening is for access 55 of air to the interior of the shell and thence to

the rotor 3 of the blower, and the capacity of the opening is controlled by a valve member 21 of curved contour conforming to the inner surface of the annular wall of the shell 11. The angular extent of the valve member 21 is sufficient to span the opening 20 in the shell 11 and, as shown, it is about 150°. The valve member includes a curved face 22 which engages the inner annular surface of the shell 11, while a marginal flange 23 of the member 21 fits approximately in the angle between the annular wall of the shell 11 and its end wall 16. The inner face of this end wall 16 has formed upon it a circular rib or bead 24 which fits just inside the edge of the flange 23 and serves as a guide for the flange 23 along which it rides as the valve member 21 is shifted around to vary the effective length of the opening 20. The opposite edge 25 of the valve member 21 fits into notched lugs 26 formed on the inner surface of the shell 11 and projecting inwardly from the face of the flange 15. The notched lugs 26, thus overhanging the marginal portion of the valve member 22 adjacent its edge 25, serves as guides to hold the valve in place while permitting it to slide circumferentially within the shell 11. One end of the valve member is formed with a V-shaped notch 27 which cooperates with the edge 18 of the opening 20 to provide a port of graduated width as the valve member 21 is slidably adjusted with relation to the edge 18; and when the notched end of the valve 21 moves away from the edge 18 there is added to the triangular area of the notch 27 a substantially rectangular area which increases as the valve member moves further away from the edge 18 of the opening 20. The size of the opening 20 is such that the end portion of the valve member 21 containing notch 27 may be easily grasped for shifting the valve manually around the shell 11, particularly, in the more widely opened positions; but as the valve is moved toward closed position so that its notched edge disappears under the edge 18 of the opening 20, it may be further manipulated by engaging the fingers in transverse recesses or channels 28 formed in the outer surface of the valve member 21 beyond the position of the notch 27 and substantially throughout the remainder of the length of the valve member 21. The valve 21 will require experimental adjustment when the burner is initially installed in order to accommodate the air inlet to the particular speed of the motor 2 and blower fan 3, and to the particular quality of the fuel oil available, but ordinarily after such initial adjustment it will be desirable to have the valve secured in position. For this purpose a clamp bar 29 extends radially against the inner face of the wall 16 with its bent end portion 30 bearing against the wall and with its opposite end 31 bearing frictionally against the flange 23 of the valve member 21. A bolt 32 extends through the clamp bar 29 and through the wall 16, being provided with a clamping nut 33 which is accessible at the outer end of the wall 16 for tightening the clamp bar 29 to secure the valve member 21 at adjusted position.

At the outer end of the air tube 7 which, as will be understood, extends into the furnace and usually into a refractory lined firebox or chamber where combustion proceeds, there is provided a tuyère structure which includes a frusto-conical choke member 35 having a cylindrical mounting portion 36 which telescopes over the end of the tube and is suitably secured thereon. Between the said portion 36 and the conical por-

tion 35, the choke member is formed with a shoulder 37 which is disposed opposite the terminal edge of the tube 7 in spaced relation thereto so as to secure in position the flat circular rim 40 of a tuyère diaphragm having inwardly extending air deflector blades 41. Each of these blades includes two approximately plane portions 42 and 43 disposed angularly to each other by bending the blade along a line 44 so that each blade is in effect a trough extending in approximately tangential relation to the circular opening 39 of the choke member. Portions of the material of the tuyère diaphragm are cut away in the form of arcuate slots 45 adjacent the flat rim 40 so that the blade areas 42 are narrowed adjacent the rim portion 40, permitting them to be bent out of the plane of the rim along the lines 46 whereby the areas 42 of the blades are inclined outwardly from the plane of the rim, that is, in the direction of discharge of the air, while the areas 43 may be considered as inclined inwardly from this plane and toward the axis of the air stream to form the troughs, as already mentioned. Thus, the portion of the air stream flowing adjacent the cylindrical wall of the tube 7 is deflected inwardly toward the axis by the conical form of the portion 35 of the choke member, and at the same time it is given a whirling motion by the tangentially disposed troughs formed by the deflector blades 41. The liquid fuel ejected from the atomizing nozzle 6 into this whirling air stream is thus further atomized and distributed to provide a readily combustible mixture which burns with an intense heat within the refractory lined chamber or firebox into which it is projected by the operation of the blower 3 and pump 5 so that when correct proportions of air and oil have been established by adjustment of the air control valve 21, substantially complete and efficient combustion of the fuel is obtained.

Incidentally, the combustion of the fuel adjacent the outer end of the air tube 7 produces intense heat which would rapidly destroy the choke member 35 and adjacent structure if they were composed of ordinary materials. We have found, however, that by using stainless steel for the choke member, and preferably for the tuyère diaphragm also, and forming the annular portion 36 of the choke member to fit over the end of the air tube 7, the extreme heat is withstood by the stainless steel parts and the material of the air tube 7 is protected against the possibility of being burned out.

As already noted, the liquid fuel is fed by the pump 5 through the pipe 8 and thence to the pipe 50 within the air tube 7 leading to the fuel discharge nozzle 6. A portion of this pipe 50 is shown adjacent the nozzle 6 in Fig. 1, and Fig. 8 shows the bent terminal portion of the same pipe 50 adjacent the coupling by which it is connected to the pipe 8. The coupling includes a threaded stem 51 with an adjacent hexagonal shoulder 52, and a reduced head portion 53 which is externally threaded. The outer end of the head 53 is formed with an annular channel 54 of V-shaped cross section which gives the central portion 55 of the head 53 a frusto-conical form dimensioned to telescope within the end of pipe 50. Usually, this pipe 50 will be a length of copper tubing and its terminal portion may be rolled over into a flange of curved cross section, as shown at 56 in Fig. 8. Before formation of the flange 56, a threaded gland member 57 is slipped over the end of the tube so that when its internal threads are engaged with the threads

on the head portion 53, the gland will force the curled flange 56 on the tubing into the channel 54, thus providing a liquid-tight joint between the interior of the pipe 50 and the bore 58 of the fitting. The threaded stem 51 extends through the side wall 9 of the chamber 10, as seen in Fig. 1, and may be suitably connected to the pipe 8 as by means of a compression coupling 60 shown in Fig. 2.

We claim as our invention:

1. A valve structure for oil burners and the like, comprising, a shell having an annular wall having an outlet at one end thereof, a transverse wall at the other end thereof, said annular wall having an elongated air inlet opening on one side extending circumferentially therein, and an elongated valve member to regulate said opening curved concentrically about said annular wall and mounted inside the shell, an annular rib projecting inwardly from said transverse wall in guiding engagement with one side of the curved valve member, lugs engaging the valve member at the opposite side of the shell and overhanging the inner surface of the valve member, thus forming guides through which said valve member is slidably adjustable to vary the effective length of the air inlet opening of the annular wall.

2. A valve structure for oil burners and the like, comprising a shell having a transverse wall and an annular wall, said annular wall having an elongated air inlet opening extending circumferentially therein, a valve member to regulate said opening curved concentrically about said annular wall and mounted inside the shell with a portion of its convexly curved surface exposed at said opening of the shell, said surface having a series of elongated, circumferentially spaced recesses extending across the valve member to serve as finger grip means by which said member may be manually engaged for sliding adjustment circumferentially of the shell, said curved valve member having an arcuate flange extending radially inwardly from its curved wall and adjacent said transverse wall of the shell, and a clamp member mounted on said wall of the shell

overlapping said flange with means to adjust said clamp into frictional holding engagement with the flange for securing the valve member at any position within its range of sliding adjustment.

3. A valve structure for oil burners and the like, comprising a shell having a transverse wall and an annular wall, said annular wall having an elongated air inlet opening extending circumferentially therein, a valve member to regulate said opening curved concentrically about the annular wall and mounted inside the shell, said valve member having an arcuate flange extending radially inwardly from its curved wall and adjacent said transverse wall of the shell, a clamp bar mounted on the inner face of said transverse wall with one end bearing thereon and with the other end of said bar bearing against said flange of the valve member together with a clamping bolt extending through the bar intermediate its ends and through said wall of the shell, and means outside the shell adjustable for tightening said bolt to draw the clamp bar into frictional holding engagement with the flange of the valve member.
